UNITED STATES PATENT OFFICE

2,574,039

MAGNETIC CENTERING DEVICE FOR
CATHODE RAY TUBESDonald Paul Ingle, Defiance, and Sol L. Reiches,
Cleveland, Ohio, assignors to All Star Products,
Inc., Defiance, Ohio, a corporation of Ohio

Application February 17, 1951, Serial No. 211,488

9 Claims. (Cl. 313—76)

1

Our invention relates to an improved device adapted to fit on the neck of a cathode ray tube to center the ray beam.

In television receivers and other apparatus intelligence is conveyed by the movements of an electron or cathode ray beam traveling over a viewing screen. In order to present the image or intelligence most effectively and to use the available screen area most efficiently, it is desirable to center the beam relative to the screen. It is not possible in practical commercial equipment to construct the apparatus so that the beam is centered, since practical manufacture, particularly of the electron gun and associated parts of the cathode ray tube, requires reasonable tolerance allowances.

For this reason it is essential in apparatus using cathode ray tubes to provide beam centering devices capable of shifting the beam within the tolerance range of the apparatus. Since the deviation of the beam from the centered value may be in any amount within the tolerance limit and may be in any direction, it is necessary that the centering apparatus be adjustable as to direction and amount of the centering shift imparted to the ray beam.

In accordance with the present invention an improved device is provided to accomplish this centering adjustment of the ray beam. Briefly, a pair of soft iron straps straddle the neck of the cathode ray tube and are snugly held thereon. The straps form a pair of non-magnetic gaps, one being bridged by non-magnetic anchoring screws and the other being bridged by a non-magnetic yoke. The straps extend radially outwardly in the region of the latter gap to define ears forming a magnet-receiving space in the region of the yoke. A permanent magnet is movably held by the yoke and is adjustable by means of a carrying rod to magnetize the straps relative to each other to create a magnetic field within the neck of the tube oriented transversely of the ray beam and having adjustable polarity and intensity.

In a modified form of the present invention, three straps encircle the neck of the cathode ray tube, the straps each extending partially about the neck of the tube and forming three non-magnetic gaps. The straps in the region of two of the gaps extend radially outwardly as described above to receive two movable permanent magnets. The resultant magnetic field within the neck of the tube can be adjusted in orientation, polarity, and intensity by suitable movement of the magnets.

2

It is therefore a general object of the present invention to provide an improved centering device for the ray beam of a cathode ray tube and providing a magnetic field of adjustable polarity and intensity.

Another object of the present invention is to provide an improved centering device for the ray beam of a cathode ray tube that is of small size and light weight and capable of being received upon and supported by the neck of the cathode ray tube.

Still another object of the present invention is to provide an improved centering device for a cathode ray tube that utilizes permanent magnets as a field producing means.

It is yet another object of the present invention to provide a very simple, compact and light weight centering means for a cathode ray tube beam which utilizes permanent magnets and produces a magnetic field of adjustable orientation, intensity, and direction.

Further it is an object of the present invention to provide an improved centering device for a cathode ray tube that is simple, inexpensive, requires no mounting elements, and is adjustable by a shaft extending backwardly of the cathode ray tube which can be made readily accessible from the rear of the television receiver or similar device and is electrically unconnected with any of the high voltage circuits of the tube.

The novel features which we believe to be characteristic of our invention are set forth with particularity in the appended claims. Our invention itself, however, both as to its organization and method of operation, together with further objects and advantages thereof, will best be understood by reference to the following description taken in connection with the accompanying drawings, in which:

40 Figure 1 is a view in perspective showing a centering device of the present invention mounted on the neck of a cathode ray tube, the device being shown in somewhat enlarged proportion in relation to the cathode ray tube;

45 Figure 2 is a side elevational view with parts in cross-section showing one form of the present invention in enlarged scale;

Figure 3 is a cross-sectional view through axis 3—3, Figure 2;

Figure 4 is a view like Figure 2 showing an alternative embodiment of the present invention;

Figure 5 is a cross-sectional view through axis 5—5, Figure 4;

55 Figure 6 is a cross-sectional view like Figures

3 and 5 showing another embodiment of the present invention.

Referring now to Figure 1, there is shown at T a cathode ray tube having a viewing screen S, a cylindrical neck N, and a base B. The tube flares between the neck N and the screen S as shown to accommodate the ray beam which sweeps across the screen S during use. As seen best in Figures 2 and 3, the tube T has electron beam producing means or electron gun located adjacent the base B, these electrodes being indicated generally at E.

The electrodes E comprise a tubular cathode 10 having its end 10a closed as shown in Figures 2 and 3. A heater unit (not shown) is positioned inside the cathode and operates, when energized, to heat the same to electron emitting temperature. The conducting sleeve 12 encircles the cathode and has an inturned portion 12a defining a circular and window through which electrons emitted from the cathode pass. This electrode forms a control grid to vary the intensity of the cathode ray beam as desired to produce the desired image on the screen S. A second sleeve 14 is mounted adjacent to and coaxially with the grid sleeve 12 and receives a positive potential in relation to the potential of grid sleeve 12. This sleeve, which acts as an electron accelerating device, has a pair of spaced inwardly extending centrally apertured disks 14a which act to limit the ray beam and partially focus the same. The last ray producing electrode is the focussing sleeve 16 which is co-axial with and slightly larger than the accelerating electrode. Sleeve 16 is positioned adjacent the end of the electrode 14 so as to define a double sleeve electron lens in conjunction therewith. The potential applied to this electrode is adjusted in relation to the potential of the accelerating electrode so as to focus the ray beam at a point on the surface of the screen S to produce a sharp spot thereon.

The foregoing elements produce a ray beam generally directed in an axial direction in relation to the tube T to impinge upon the screen S. However, in practical commercial tubes, it is not possible to secure precise alignment and there is a certain amount of inevitable deviation from this condition. It is the purpose of the mechanism of the present invention to correct for this deviation in a highly effective and yet inexpensive and convenient manner.

In the form of the present invention shown in Figures 1 to 3, a pair of soft iron straps 18 and 20 of shape to conform to the shape of the neck of the tube and in the form of two halves extend about the neck of the tube. These straps extend radially outwardly at their ends in ears forming two sets or pairs of plane faces, as indicated at 18a, 18b, 20a, and 20b. The faces 18a and 20a are apertured and receive the screw 22 and nut 24 which can be tightened or loosened to grip the neck N as desired.

At portions 18b and 20b, the straps 18 and 20 form a cavity. The yoke 26 of brass, plastic, or similar non-magnetic material, is sandwiched between these portions of the straps as shown to form a non-magnetic spacer. The portions 18b and 20b are secured to this spacer by the rivets 27, thus forming a rigid cage.

The web portions 26c of the yoke 26 has a bore 26d disposed coaxially with the cage formed by the parts 18b and 20b. This bore forms a bearing which receives the shaft 28 which extends into the space between portions 18b and 20b of the

straps 18 and 20 in an enlarged portion 28a. A permanent magnet 30, described hereafter, is positioned on the end of this shaft as shown. An outrigger shaft 32 has an end bore 32a which is received over the protruding end of the shaft 28 and is rigidly secured thereto by the set screw 34 which is threadedly received by the shaft 32. The outrigger shaft 32 may be of insulating material if the unit is not grounded and of conducting material if the unit is grounded.

The magnet 30 is of any efficient permanent magnet material such as, for example, "Alnico," which is an alloy of aluminum, nickel, and cobalt. This magnet is of such cross-section that it can be made to produce opposed faces magnetized in opposite polarity. In a cross-section such as shown in Figure 3, face 30a is of one polarity, say north, and face 30b is of opposite polarity, say south. Thus, when faces 30a and 30b are aligned with portions 18b and 20b of the straps 18 and 20, respectively, strap 18 is a north pole and strap 20 a south pole and the space between the straps (and hence the interior of the neck N) has a corresponding magnetic field. Similarly, when the shaft 32 is rotated 180° from this position to locate face 30a adjacent portion 30b of the strap 20 and the face 30b adjacent portion 18a of strap 18, the latter strap is a south pole and strap 20 is a north pole, thus giving rise to a magnetic field of opposite polarity.

When the shaft 32 is adjusted to orient the faces 30a and 30b to an intermediate position as shown in Figure 3, the magnet 30 is less effective in producing a magnetic field within the confines of the neck N of the tube because the leakage flux between the magnet poles is greater. When the faces 30a and 30b are vertically one above the other, the field is of zero intensity within the neck N. Thus rotation of the magnet 30 varies the polarity and the intensity of the magnetic field within the neck N of the tube.

The ray beam from the electron gun E travels at high velocity in the direction of the arrow 36, Figure 2. Since the magnetic field between the straps 18 and 20 is oriented transversely to this direction of travel, the beam is deflected up or down as shown by the arrow 38, Figure 3, the amount and direction of this deflection being dependent on the position of the shaft 32. Consequently, the shaft may be rotated until the ray beam strikes the desired center point of the cathode ray tube screen S, thus compensating for eccentricities in the tube.

The magnetic sweep device 40, Figure 1, produces a magnetic field as required to direct the ray beam in the desired motion across the screen S. In television service, for example, this motion is a repetitive straight line scanning cycle. If this portion of the unit introduces any eccentricity or shift of the ray beam when in the energized condition, the beam can be restored to the centered condition by appropriate rotation of the shaft 32. In other words, the shaft 32 can be rotated to compensate not only for tolerances in the cathode ray tube itself but also in the deflecting devices or the electric circuits energizing them and various stray fields such as the earth's field.

The unit shown in Figures 1 to 3 is capable of shifting the ray beam in one direction in the amount required to center the beam. An additional unit may be used if desired to center the beam in the opposite direction, this being offset approximately 90° in relation to the first unit. Alternatively, the straps 18 and 20 may be held on the neck N of the tube T rather loosely and the

unit rotated until the direction of the field between the straps is transverse to the eccentricity of the ray beam. The beam may then be centered by appropriate rotation of the shaft 32.

Figures 4 and 5 show an alternative embodiment of the structure of the present invention. In this figure parts corresponding to those of Figures 1 to 3 are identified with the number 100 added to the identifying numeral. The structure of Figures 4 and 5 differs from that of Figures 1 to 3 in that the ears 118b and 120b extend out from neck N so as to define a channel 119 in conjunction with the portions of 126a and 126b of yoke 126.

The web 126c of the yoke 126d is of such cross-section so as to prevent rotation of the magnet assembly. The rod 128 is slidably received in this opening and carries at its end a bar magnet 130 of cross-section as is described on page 7, lines 11, 12, 13. An outrigger shaft 132 has an opening which receives the end of shaft 128 and is secured thereto by the set screw 134 as shown so that the shaft 132 may be shifted forwardly or backwardly to alter the position of the magnet 130 in relation to the straps 118 and 120. This outrigger shaft may be of insulating material if the unit is not grounded and of conducting material if the unit is grounded.

The magnet 130 is of Alnico V (an aluminum, nickel, cobalt alloy) or similar efficient permanent magnet material. One end, say end 130a, is magnetized to form a north pole on face 130c and a south pole on face 130d. The other end, 130b, is oppositely magnetized to form a south pole on face 130c and a north pole on face 130d. When the shaft 132 is shifted, to cause ends 130a and 130b to move in relation to the straps 118 and 120, the straps are magnetized in accord with the portion of the magnet 130 in registry with the ears 118b and 120b. The polarity of the field is in one direction (strap 116 north, strap 118 south) with end 130a between ears 118b and 120b and the opposite direction with the end 130b between the ears. At intermediate positions the intensity of the field is less than at the extreme positions but the polarity is in accord with the end of the magnet nearest the straps 116 and 118.

The unit of Figures 4 and 5 operates to deflect the ray beam up or down as shown by the arrow 138. If it is desired to deflect the beam in two directions, a second unit, transverse to the first and offset lengthwise along neck N may be employed.

Figure 6 shows another embodiment of the present invention capable of shifting the ray beam in any direction on the screen S, Figure 1. This unit includes three soft iron straps 218, 219, and 220, each extending partially about the neck N of the tube and each having ears extending radially outwardly as shown at 218a, 218b, 219a, 219b, 220a, and 220b. The ears 218a and 220b receive the screw 222 and nut 224 to secure the unit to the neck of the tube by adjustable compression.

The ears 218b and 219a and the ears 219b and 220a are like the ears 18b and 20b, Figure 3, to form a cavity. The ears are held in position by the non-magnetic yokes 226 which are like the yoke 26, Figure 1. Magnets 230 are rotatably mounted within each cage so defined in the same manner as the magnet 30, Figures 2 and 3, these magnets being magnetized like magnet 30 so that their opposite faces have opposite polarities.

The operation of the unit of Figure 6 can be

visualized by considering the operation of the magnets 230 separately. The magnet within the cage formed by the ears 218b and 219a acts to magnetize straps 218 and 219 to produce a field in the center of the tube extending generally in the direction of arrow 200, thus providing control of the position of the ray beam in the direction transverse to this arrow. Similarly the magnet within the cage formed by the ears 219b and 220a acts to magnetize straps 220 and 219 to produce a field at the center of the tube extending generally in the direction of arrow 202, thus providing control of the position of the ray beam in the direction transverse to this arrow. Together, the magnets control the position of the ray beam in both directions and thereby control the centering of the ray beam in each direction on the screen S.

It will be noted that the magnet 130 is approximately twice the width of the straps 118 and 120 so that one half or the other of this magnet can be centered within the confines of the space formed by the ears 118b and 120b.

If desired, a cushion such as a plastic sleeve encircling the straps may be interposed between the straps of the centering device and the neck N of the tube, thus permitting control of the grip of the straps on the tube without undue risk of tube breakage.

The term ferro-magnetic is used herein to designate materials, such as soft iron, having a high magnetic permeability in relation to air but no undue tendency for a residual magnetization. The term non-magnetic is used to designate materials such as plastics, brass, aluminum, and the like which have very low permeability in relation to ferro-magnetic materials.

While we have shown and described specific embodiments of our invention, it will of course be understood that numerous variations and alternative constructions may be made without departing from the true spirit and scope thereof. We therefore intend by the appended claims to cover all variations and alternative embodiments falling within the true spirit and scope of the appended claims.

What we claim and desire to secure by Letters Patent of the United States is:

1. A magnetic centering device for a cathode ray tube having a neck containing electron beam producing means comprising in combination, a pair of ferro-magnetic straps adapted to straddle the neck of the tube and, in position, defining a pair of circumferentially spaced gaps, the straps extending radially outwardly at one of the gaps to form a pair of ears with opposed faces, non-magnetic yoke means securing said faces in spaced relation to form a magnet-receiving space and forming a non-circular guideway extending parallel to the neck of the tube; and a rod snugly received in said guideway for shifting movements parallel to the neck of the tube and carrying on its end and partially within the confines of said magnet-receiving space a permanent magnet of length approximately twice the length of the space and having oppositely directed magnet poles at its ends cooperable respectively with the ears to magnetize the straps.

2. A magnetic centering device for a cathode ray tube having a neck containing electron beam producing means comprising in combination, three ferro-magnetic straps adapted to encircle the neck of the tube and, in position, each extending partially about the same and defining

three circumferentially spaced gaps, the straps extending radially outwardly at two of the gaps to form pairs of opposed ears, non-magnetic means securing said faces in spaced relation to form a pair of magnet-receiving spaces, and permanent magnets movably mounted within said space to create a magnetic field of adjustable orientation, intensity, and direction between the straps and transverse of the ray beam.

3. A magnetic centering device for a cathode ray tube having a neck containing electron beam producing means comprising in combination, three ferro-magnetic straps adapted to encircle the neck of the tube and each extending partially about the same and, in position, defining three circumferentially spaced gaps, the straps extending radially outwardly at two of the gaps to form pairs of opposed ears, and permanent magnets movably mounted within said two gaps and individually adjustable to create a magnetic field of adjustable orientation, intensity, and direction, between the straps and transverse of the ray beam.

4. A magnetic centering device for a cathode ray tube having a neck containing electron beam producing means comprising in combination, a pair of ferro-magnetic straps adapted to straddle the neck of the tube, and in position, defining a pair of circumferentially spaced gaps, the straps extending radially outwardly at one of the gaps to form a pair of ears with opposed faces, non-magnetic yoke means securing said faces in spaced relation to form a magnet-receiving space and forming a non-circular guideway extending parallel to the neck of the tube, and a permanent magnet slidably received in said guideway and having oppositely directed pairs of magnet poles spaced in the direction of sliding and selectively cooperable with the ears to magnetize the straps in controllable amount and polarity.

5. A magnetic centering device for a cathode ray tube having a neck containing electron beam producing means, said device comprising, in combination, a pair of unitary complementary ferro-magnetic straps spaced relative to each other to straddle the tube and, in position, defining a pair of circumferentially spaced gaps, one gap extending a substantial distance radially of the tube to form a magnet-receiving space, non-magnetic yoke means sandwiched between the straps to sustain the same in fixed relative position at said one gap, and a permanent magnet having faces of opposite polarity disposed in said one gap and carried by the yoke means for rotations about an axis parallel to the tube for rotations to positions of adjustable registration with the ends of the straps defining said one gap, thereby to vary the intensity and polarity of the magnetic field within the tube.

6. A magnetic centering device for a cathode ray tube having a neck containing electron beam producing means, the device comprising in combination, a pair of like unitary complementary ferro-magnetic straps adapted to straddle the neck of the tube and conform snugly to the surface thereof to define a pair of relatively small diametrically opposed circumferential gaps, the straps having ears extending a substantial distance radially outwardly in the region of one gap to form a magnet receiving space, non-magnetic means securing the straps together in fixed relative position at the opposite ends of the magnet-receiving space, and a permanent magnet having faces of opposite polarity carried by said means in the magnet receiving space for rotations about

an axis parallel to the tube axis to vary the intensity and direction of the magnetic field within the tube.

7. A magnetic centering device for a cathode ray tube having a neck containing electron beam producing means, the device comprising in combination, a pair of like unitary complementary ferro-magnetic straps adapted to straddle the neck of the tube and conform snugly to the surface thereof to define a pair of relatively small diametrically opposed circumferential gaps, the straps defining radially extending ears in the regions of said gaps, one pair of ears being of relatively small radial extent, adjustable non-magnetic securing means extending between said one pair of ears, the other pair of ears being of relatively great radial extent to form a magnet receiving space, non-magnetic means securing the straps together at fixed spacing at said other pair of ears, and a permanent magnet having faces of opposite polarity carried by said means in the magnet-receiving space for rotations about an axis parallel to the tube axis to vary the intensity and direction of the magnetic field within the tube.

8. A magnetic centering device for a cathode ray tube having a neck containing electron beam producing means, said device comprising, in combination; a pair of ferro-magnetic straps having complementary arcuate portions adapted to straddle the neck of the tube and substantially radial complementary portions contiguous therewith defining spaced ears, a non-magnetic yoke sandwiched between said ears to sustain them in fixed relative position, and a permanent magnet having faces of opposite polarity registerable with the ears respectively and movably carried by the yoke, the magnet being in spaced relation with the ears at all times.

9. A magnetic centering device for a cathode ray tube having a neck containing electron beam producing means, said device comprising in combination; ferro-magnetic strap means defining complementary arcuate portions adapted to straddle the neck of the tube and substantially radial portions contiguous therewith defining spaced ears, a permanent magnet having faces of opposite polarity cooperable with the ears respectively to magnetize the arcuate portions of the strap means, and elements fixedly supported in relation to the ears supporting the magnet for field adjusting motions with respect to the ears and sustaining the ears in fixed relative position independent of magnet movement.
